CONVERTIBLE TABLE

Hans Weiss, New York, N. Y.

Application October 7, 1948, Serial No. 53,160

1 Claim. (Cl. 311—39)

1

This invention relates to new and useful improvements in articles of furniture of the table class, and, more particularly, the aim is to provide a novel and valuable table which, having a non-folding top for support by and above a plurality of legs, as four thereof, is so constructed that, without removing any part of the top or disconnecting it from the legs, the top may be readily raised from a lower elevation to a higher elevation and vice versa, thereby, as the case may be, to provide a rigidly established and sturdy table having its top at a height characteristic of a bridge or dining table, or to provide a rigidly established and sturdy table having its top at a height characteristic of a so-called coffee table.

A further object is to provide a table having between its legs and its top an intermediate structure which may be readily expanded to lift the top to a higher height or collapsed to lower the top to a less height simply as the result of raising or lowering the top.

Still another object is to provide a table as above, wherein the weight of the top and of associated parts holds said intermediate structure collapsed when the table is a lower height one, and wherein there is provided a single rotative element, which may be mounted for rotation on the table top at its underside, for being given a turn through a small fraction of a revolution thereby to securely lock said intermediate structure in its expanded condition to establish a higher height table.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a top plan view of a now favored embodiment of the invention, with the table top partially broken away.

Fig. 2 is a side elevational view looking in the direction of the line 2—2 of Fig. 1.

Fig. 3 is a view similar to Fig. 2, but showing the table top in course of being raised thereby automatically to expand the intermediate structure.

Fig. 4 is a horizontal section taken on the line 4—4 of Fig. 3; but here the table top is shown in dot and dash lines.

Fig. 5, also a view similar to Fig. 3, shows the

table top fully raised and the intermediate structure fully expanded.

Fig. 6 is a horizontal section taken on the line 6—6 of Fig. 5.

Fig. 7 is an enlarged detail perspective view, showing portions of the two members of one of the four pairs of interhinged members constituting said intermediate structure, and more particularly for showing one of the piano-type hinges employed between said members and elsewhere in the new table.

Fig. 8 is a still further enlarged detail view, this being a fragmentary vertical section taken on the line 8—8 of Fig. 1.

Referring to the drawings in detail, a table pursuant to the invention is illustratively shown as having a square one-piece top 10, and a base having four legs 11, with such legs constituted as vertically dependent extensions from an integral with a four-armed skeletal or spider frame 12 lying generally in a horizontal plane, and, as here shown, with the upper ends of each leg curvilinearly merging with the outer end of one of the four radially equally diverging arms of the frame 12.

Each of the aforesaid four pairs of interhinged members constituting the intermediate structure is alike, and a description of one such pair will suffice as a description of all.

Consider, for example, the pair of said members shown at the upper right in Fig. 1, and at the right in Figs. 2, 3, 4 and 5. Said pair comprises an upper elongate member 14 of rectangular shape, and a lower member 15 which is preferably a duplicate of the member 14, as to length, width and thickness, with the upper and lower ends of each member parallel with each other and perpendicular to the general plane of extension of the member.

The lower one of each of the four pairs of such members is connected at its lower end (in Figs. 3 and 4) to and at the top of a different one of the four arms of the frame 12, by a piano-type hinge; the upper end of said lower member is connected to the lower end of the upper member by a similar hinge; and the upper end of said upper member is connected by a similar hinge to the underside of the table top 10. In the case of the particular pair of members selected for detailed description as above, the first-mentioned of said three hinges is marked 16, the second-mentioned one thereof is marked 17, and the third-mentioned one thereof is marked 18. The hinge 17 is clearly shown in Fig. 7.

The four pairs of inter-hinged and hinged

attached members of the intermediate structure, each of which members may be called a link member, are, it will be noted, spaced 90° apart, and equally radially displaced from the center of the table top, and in such manner that when the parts are arranged as in Fig. 5, the two link members of each of said four pairs of members are vertically in line, so that then each of said pairs presents a vertically upstanding sub-structure squarely facing another such sub-structure spaced 180° therefrom.

Suitably pivotally mounted on the table top 10 at the underside thereof, as at 19, is a flat plate-like cruciform member 20. The axis of pivoting of such member is at the center of the top 10, and hence equally spaced from the hinge 16 and the corresponding hinges of the three other pairs of link members and from the hinge 18 and the corresponding hinges of the other three pairs of link members.

The four arms of the cruciform member 20 are all of equal length, and of such length that, after the intermediate structure has been erected as in Fig. 5, a rotation of said member 20, as in the direction of the arrow 21, through 45°, from its normal position indicated in dot and dash lines in Fig. 6 (this being its position also indicated in Fig. 1), to its full line position in Fig. 6, the slightly rounded ends of said arms frictionally and dependably engage the inner faces of the members 14 and thereby to lock the latter in the condition shown in Fig. 5.

Thus, to transform the table from the condition shown in Fig. 2 to the condition shown in Fig. 5, to provide a bridge or dining table, it is merely necessary fully to lift the top 10, and then fractionally rotate the cruciform member 20 as just described. Note, as shown in Fig. 8, that, with the plate of the hinge 18 which is attached to the top 10 set in an accommodating recess 22 in the underside of the top, and with the pintle-engaging curls of the hinge disposed as shown, the presence of the hinge does not interfere in any way with approach of the outer end of an arm of the member 20 to the intended frictional engagement thereof with the member 14 as illustrated in Fig. 6.

To transform the table from the condition shown in Fig. 5 to the condition shown in Fig. 2, to provide a coffee table, it is merely necessary to turn the cruciform member 20 through say 45°, as in the direction opposite to that of the arrow 21 of Fig. 6, and, for instance, to dispose said member in the position shown in dot and dash lines in Fig. 6; and then lower the table top 10 a distance sufficient to cause a slight inward inclination of the member 14, that is, to cause a slight simultaneous knee-action collapse of the four pairs of inter-hinged link members of the intermediate structure, whereupon, by the weight of the table top and of the parts between the same and the frame 12, the table will collapse fully as shown in Fig. 2.

At that time, it being noted that the plate of the hinge 16 which is attached to the top of the associated arm of the frame 12 is set in an accommodating recess in the said arm as explained in connection with the hinge 18, the then bottom face of the member 15 will extend horizontally and lie flat on the frame 12; the member 14 will lie flat on the member 15, and the then upper

5 face of said member 14 will extend horizontally and lie flat against the flat underside of the top 10. This ideal condition will be present also at each of the other three pairs of inter-hinged members of the intermediate structure.

10 While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:

15 In a table having a base and a table top resting on the top face of the base, means interposed between the base and the top for holding the top in a position raised off the base, comprising a plurality of extendable members having superimposed elongated members between the base and the table top and arranged in a circle with their lengths extended radially, said superimposed members having their inner ends pivotally connected together, the uppermost of said superimposed members having their outer ends pivoted on the bottom face of the table top and the lowermost of said superimposed members having their outer ends pivoted on the top face of the base, whereby when the table top is raised off the base said superimposed members pivot relative to each other and relative to the base and the table top and become vertically disposed retaining the table top in its position raised off the base, and means on the bottom face of said table top for releasably retaining said extendable members against collapsing when the table top is in its raised position, said releasable retaining means comprising a member having a radially extending arm for each of said extendable members, said member being turnably mounted on the bottom face of the table top at the center of the area defined by the pivotal mounting of the outer ends of the uppermost of said superimposed members with said radially extending arms between said extendable members, whereby when the table top is in its raised position said latter member can be turned to engage the free ends of said radially extending arms behind the uppermost of said superimposed members.

50 HANS WEISS.
